UNITED STATES PATENT OFFICE.

MARY A. MULLIGAN AND JENNIE S. MULLIGAN, OF ST. PAUL, MINNESOTA.

DESIGN FOR AN APRON.

40,967.

Specification for Design.

Patented Nov. 1, 1910.

Application filed September 20, 1909. Serial No. 518,720. Term of patent 7 years.

To all whom it may concern:

Be it known that we, MARY A. MULLIGAN and JENNIE S. MULLIGAN, citizens of the United States, residing in the city of St. Paul, county of Ramsey, and State of Minnesota, have invented a new, original, and ornamental Design for Aprons, of which the following is a specification, reference being had to the accompanying drawing, forming part thereof.

The figure is a plan view of an apron showing our new design.

We claim:

The ornamental design for an apron as shown.

MARY A. MULLIGAN.
JENNIE S. MULLIGAN.

Witnesses:

W. H. WILLIAMS,
G. S. HANSEN.
